UNITED STATES PATENT OFFICE

ARTHUR J. FLINT AND FRED C. GILLETTE, OF BOSTON, MASSACHUSETTS.

PIANOFORTE-ACTION.

SPECIFICATION forming part of Letters Patent No. 668,508, dated February 19, 1901.

Application filed June 14, 1900. Serial No. 20,349. (No model.)

To all whom it may concern:

Be it known that we, ARTHUR J. FLINT and FRED C. GILLETTE, of Boston, in the county of Suffolk and State of Massachusetts, have 5 invented a new and useful Improvement in Pianoforte-Actions, of which the following, taken in connection with the accompanying drawings, is a specification.

Our invention relates to the arrangement 10 and construction of the under hammer, jack-fly, and connected parts of a pianoforte-action, the object being to so simplify and improve these portions of the action that the whole is made better, more durable, and 15 cheaper. This object we attain by means of the mechanism shown in the accompanying drawings, in which—

Figure 1 is a side elevation of the parts that constitute one of our improved actions, the 20 rails being shown in section. The hammer is shown in its resting position—that is, down. Fig. 2 is also a side elevation of the parts, the hammer being represented as in the position that it occupies just after striking the wire, 25 all the parts being ready for a “repeat.” Fig. 3 shows some of the parts in the position that they occupy when the key is pressed down to its lowest limits and when the jack-fly lever is at its highest position. Fig. 4 is 30 a front elevation of the jack-fly, showing its peculiar construction.

In the drawings a key K, of ordinary construction, is shown. This key has an adjustable support K' for the jack-fly lever E. The 35 said lever E is pivoted at A² to the flange A' on the rail A. The jack-fly lever E has a bracketed standard E', to the upper end of which the under hammer C is pivoted by the pivot C'. The movement of the under hammer 40 in relation to the jack-fly lever is regulated by the adjusting-screw D, the head or button of which comes in contact with the bracket-arm standard E'. A spring S serves to keep the working end C² of the under hammer up, so as to sustain the hammer in the 45 position required for repeat after the jack-fly has left the cushion H² of the hammer-but. (See Fig. 3.) The absolute upward movement of the working end C² of the under hammer 50 is governed by the extension-arm C⁵, which, passing through a slot in the jack-fly, comes in contact with the adjustable button

C⁴ of the adjusting-screw C⁶ in the fixed hammer-rail R. The extension-arm C⁵ is made of wire bent and flattened, as shown, where- 55 by it admits of being located centrally in a slot made in the jack-fly and also of serving to reach out to a point under the hammer-rail R, adapting it to be controlled by the adjustable button C⁴ of the adjusting-screw C⁶ 60 in the fixed hammer-rail R.

The stem H of the hammer H' is pivoted at H³ to the flange H⁴, which is secured to the hammer-rail R in the usual manner. In its resting position the hammer-stem H rests 65 upon the cushion of the spring-rail B.

The jack-fly F has a slot, as shown at T, Fig. 4, through which the extension-arm C⁵ of the under hammer extends. This particu- 70 lar arrangement of the arm C⁵ and the slot in the jack-fly simplifies the construction and affords an additional steadiness and strength to the action and secures a firm broad bearing for the cushion H² of the hammer-but on the end of the jack-fly. 75

The jack-fly F is pivoted to its lever E by the pin F'. Its upper end is held against the adjusting-button C³ on the end of the under hammer C. The spring F³ has a tendency to draw the upper end of the jack-fly toward and 80 against (when permitted) the adjusting-but- 85 ton C³ at the end C² of the under hammer C. The upper end of the jack-fly is thrown out from under the cushion H² of the hammer-but by the foot F² (which is a part of the jack-fly) as it comes in contact with the but- 90 ton L² on the screw L' in the rail L. (See Fig. 3.)

We claim—

1. In a pianoforte-action a jack-fly lever 90 having a bracketed standard; an under ham- mer pivoted to said standard, and having an upwardly-extending working end (as C²) adapted to operate on the hammer as de- 95 scribed and provided with an adjusting-but- ton (as C³) for controlling the jack-fly; an arm (as C⁵) extending through a slot made in the jack-fly, which serves to limit the upward motion of the said under hammer and said jack-fly substantially as and for the purpose 100 set forth.

2. In a pianoforte-action a jack-fly lever; an under hammer pivoted to said jack-fly le- 100 ver and having inserted in its end a wire

which forms an extension for the said under hammer and passes through a slot made in the jack-fly to a point under the hammer-rail whereby the motion of the said under hammer may be limited by an adjustable button attached to said hammer-rail, and said adjustable button and hammer-rail substantially as and for the purpose set forth.

In testimony whereof we have signed our

names to this specification, in the presence of two subscribing witnesses, on this 12th day of June, A. D. 1900.

ARTHUR J. FLINT.
FRED C. GILLETTE.
